FIG. 1

FIG. 2

FIG. 3

FIG. 4

FIG. 5

FIG. 6

FIG. 7

FIG. 8

FIG. 9

FIG. 1 is a front, top and right side perspective view of our handsfree telephone subset, showing our new design with the handset in place;

FIG. 2 is a fragmentary front, top and right side perspective view with the handset omitted;

FIG. 3 is a fragmentary top plan view;

FIG. 4 is a fragmentary rear, top and left side perspective view;

FIG. 5 is a fragmentary front elevational view;

FIG. 6 is a fragmentary rear elevational view;

FIG. 7 is a fragmentary right side elevational view;

FIG. 8 is a fragmentary bottom, left side and front perspective view; and

FIG. 9 is a cross-sectional view of the transducer grill taken at 9-9 in FIG. 1. This view is representational of the grills at the front and rear of the telephone.

The handset has been omitted from all figures except FIG. 1 for convenience in illustration.

The handset cord in FIG. 1 is partly broken away as indicated by the dot-dash lines for convenience of illustration.

We claim:

The ornamental design for a handsfree telephone subset, as shown and described.
